CLAIM

The ornamental design for a pan, as shown and described.

DESCRIPTION

FIG. 1 is a perspective view of the claimed design.

FIG. 2 is a top view of the claimed design.

FIG. 3 is a bottom view of the claimed design.

FIG. 4 is a left view of the claimed design.

FIG. 5 is a front view of the claimed design.

FIG. 6 is a back view of the claimed design.

FIG. 7 is a right view of the claimed design.

FIG. 8 is a perspective view of the claimed design.

FIG. 9 is a top view of the claimed design.

FIG. 10 is a bottom view of the claimed design.

FIG. 11 is a left view of the claimed design.

FIG. 12 is a front view of the claimed design.

FIG. 13 is a back view of the claimed design; and,

FIG. 14 is a right view of the claimed design.
